US00D817476S

(12) **United States Design Patent** (10) **Patent No.:** **US D817,476 S**
(45) **Date of Patent:** **** May 8, 2018**

(54) **CEILING FAN BLADE IRON**

(71) Applicant: **HUNTER FAN COMPANY**,
Memphis, TN (US)

(72) Inventor: **Christine Holmes**, Memphis, TN (US)

(73) Assignee: **Hunter Fan Company**, Memphis, TN
(US)

(**) Term: **15 Years**

(21) Appl. No.: **29/604,233**

(22) Filed: **May 16, 2017**

Related U.S. Application Data

(62) Division of application No. 29/550,954, filed on Jan.
8, 2016, now Pat. No. Des. 796,024.

(57) **CLAIM**

The ornamental design for a ceiling fan blade iron, as shown and described.

DESCRIPTION

FIG. 1 is a top perspective view of a ceiling fan blade iron showing my new design;

FIG. 2 is a bottom perspective view of the ceiling fan blade iron of FIG. 1;

FIG. 3 is a rear view of the ceiling fan blade iron of FIG. 1;

FIG. 4 is a front view of the ceiling fan blade iron of FIG. 1;

FIG. 5 is a left side view of the ceiling fan blade iron of FIG. 1;

FIG. 6 is a right side view of the ceiling fan blade iron of FIG. 1;

FIG. 7 is a top view of the ceiling fan blade iron of FIG. 1; and,

FIG. 8 is a bottom view of the ceiling fan blade iron of FIG. 1.

Portions of the ceiling fan blade iron shown in broken lines form no part of the claimed design.

1 Claim, 8 Drawing Sheets
